AUTOMOBILE WASHER OR SIMILAR ARTICLE

Max Fruchter, Springfield, N.J.

Application May 13, 1958, Serial No. 50,866

Term of patent 14 years

(Cl. D49—1)

Figure 6

Figure 1 is a front elevational view of an automobile washer or similar article, showing my new design;

Figure 2 is a right end view thereof;

Figure 3 is a rear elevational view thereof;

Figure 4 is a left end view thereof;

Figure 5 is a top plan view thereof;

Figure 6 is a transverse vertical section through the center of Fig. 1.

The elements shown in the dotted lines on the side supports in Fig. 1 are omitted for the purpose of convenience of illustration in Figs. 2, 3, 4, 5 and 6.

The dominant features of my design reside in the portions shown in full lines.

I claim:

The ornamental design for an automobile washer or similar article, as shown and described.
